UNITED STATES PATENT OFFICE.

SAMUEL NELSON, OF WATERLOO, IOWA.

DESIGN FOR A SPECTACLE FRAME OR SIMILAR ARTICLE.

Application filed March 30, 1926. Serial No. 17,115. Term of patent 14 years.

To all whom it may concern:

Be it known that I, SAMUEL NELSON, a citizen of the United States, residing at Waterloo, in the county of Blackhawk, and State of Iowa, have invented a new, original, and ornamental Design for Spectacle Frame or Similar Article, of which the following is a specification, reference being had to the accompanying drawings, forming a part thereof.

Figure 1 is a front elevation of a spectacle frame or similar article embodying my new design,

Figure 2 is a rear elevation of the same, Figure 3 is a plan view of the same, and, Figure 4 is an end elevation of the same.

I claim:

The ornamental design for a spectacle frame or similar article as shown.

SAMUEL NELSON.
